MACHINE FOR FRAMING HANDBAGS

Eric M. Kass, New York, N. Y.

Application December 3, 1941, Serial No. 421,461

10 Claims. (Cl. 153—1)

This invention relates to the art of framing handbags and to machines for clamping frame members on bags.

One object of the invention is to provide for the improved clamping of frame members on handbags in a rapid and convenient manner and without scratching or marring the frame members as heretofore.

Another object of the invention is to provide for the clamping of the frame members under a constant or predetermined pressure to produce a uniform unimpaired product without cutting of the bag and without requiring repeated clamping strains on each part of the frame members.

Another object of the invention is to provide for the clamping of the frame members by automatic or motorized power for an instantaneous improved clamping operation with a deformation solely of the normally concealed flange of the channel frame member.

Another object of the invention is to provide for the preliminary holding or gripping of the frame member in an automatic but preferably manually releasable manner for insertion and removal of the frame member relative to the jaws, so that the actual clamping action shall occur without movement or slippage of the frame member to avoid marring and scratching thereof and to permit the framing to be accomplished in a rapid labor-saving manner.

Another object of the invention is to provide for the clamping of a straight section of a U-shaped frame member in one operation, including the corner portions of the frame member.

Another object is to provide for the improved powerful clamping of the frame members as by a toggle-like action.

Another object is to provide for the clamping to be performed along an inclined table to facilitate the handling of the frame and its bag.

A further object is the provision of improved apparatus to realize all of the above stated objects, with the apparatus being compact, durable, inexpensive, reliable and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the

same reference characters throughout the several views.

In the drawing:

Figure 1 is a view in front elevation showing a machine embodying the invention, in the clamping position thereof.

Fig. 2 is a view in side elevation thereof.

Fig. 3 is an enlarged fragmentary view of the machine with parts in section, but showing the power means retracted and the movable jaw manually retracted.

Fig. 4 is a diagrammatic view showing a frame member supported for clamping with the jaw extended to clamp the corners of the frame member.

Fig. 5 is a similar view showing the clamping of the arms of the frame.

Fig. 6 is an enlarged view with parts in section and parts in elevation showing the clamping of a frame member on a bag.

Fig. 7 is a similar view showing the clamping of a different type of frame member on a bag.

Figs. 8 and 9 are fragmentary sectional views of the handbags produced according to Figs. 6 and 7, respectively.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a machine embodying the invention. The same may include a frame 11 comprising a base 12 having an extension 13 carrying an electrical motor 14. At the top of the frame is a bearing 15 for a shaft 16 carrying a large flywheel or pulley 17 which is engaged as by a belt or chain 18 with a small pulley 19 of the motor 14.

Carried by the shaft 16 is an eccentric or cam 20 having a yoke 21 carrying a plunger 22 that is thus reciprocated thereby. A head 23 may be connected to the plunger as by an adjustable powerful screw 24 to set the position of the head.

For guiding the latter, the frame 11 may have flanges or guides 25 providing any suitable pathway with which the head may slidingly engage to impart the power stroke for clamping of the frame members.

Fixed on the frame 11 is a bracket 26 provid-

ing a downwardly and forwardly inclined seat 27. On the extreme end of the bracket is fixed an interchangeable jaw 28 with which coacts a movable interchangeable jaw 29. Carrying the latter is a slide 30 resting on the seat 27 and being guided in a yoke 31 suitably affixed to the bracket 26. At its exposed rear end, the slide 30 may terminate in an enlargement or head 32 against which bears an expansion coil spring 33 that is also attached to the lug 34 of the bracket. For clearance at the spring, the bracket may have a recess 35.

Since the spring 33 urges the movable jaw 29 into engagement with the fixed jaw 28, manual means is provided for retracting the movable jaw. For this purpose I provide on the bracket 26 a lug 36 to which a lever 37 is pivotally connected at 38, one end of the lever being pivotally connected to the link 39 which is pivotally connected at 40 to the member 32. To the other end of the lever 37 is fixedly connected an arm 41 which is so arranged as to be movable by the knee of the operator so that a rightward movement causes retraction of the jaw 29.

To permit manual retraction to occur without interference by the power means, the head 23 is separate of the slide 30 but engageable therewith and in spaced relation thereto in the retracted position of the power means. For this purpose an abutment member or bar 42 is pivotally connected at one end to the head 23 as at 43, while the other end movably abuts the member 32 in a recess at 44 and is slidably retained therein by the overlying link 39. Desirably a toggle may be employed comprising a supplemental link 42a also pivoted at 43 and swingably abutting in a recess 42b of the frame 11. The action of the toggle 42, 42a requires an angular freedom at the power head, and therefore the head 23 may be pivotally mounted, for example, on the screw 24 as by any suitable means 43a. As the link 42 is moved downward, a powerful forward thrust is exerted which increases with the downward movement.

By reason of the inclined position of the seat 27, there is formed an obtuse angle with the path of the head 23 to obtain a powerful toggle like action, the member 42 acting in a manner analogous to a link and oscillating as the head 23 reciprocates. If Figs. 1 and 2 be regarded as showing the jaw 29 advanced to its clamping position, but with the handbag frame omitted for clarity in the drawing, Fig. 3 shows the head 23 and the member 42 retracted but the jaw 29 urged into holding position on the frame by the spring 33, the frame being here also omitted for clarity. The starting and stopping of the power means may be effected as by a switch box 45 on the base 13 wired to the motor at 45a and controlled by a foot lever 46 pivoted at 47 on said base and urged by a tension coil spring 48 into position to open the switch and stop the motor. Additional control means may be provided such as a clutch or brake or both to assure the stopping of the head 23 in its proper retracted position, but these being conventional need not be shown herein.

To adjust a bendable fastener knob-like closure element on the frame member an abutment member such as 49 may be removably fixed on the movable jaw 29 particularly as shown in Fig. 6 to bend and adjust the closure member coincident with the clamping power impulse.

The manner of using the machine will now be described, with particular reference to Figs. 4 to

9. The general type of frame herein referred to is shown in Figs. 4 and 5 and consists of a pair of U-shaped channel frame members 50 hinged together at 51, and each having a top section 52 and a pair of depending arm sections 53. Frames so constructed may have differently arranged channels as indicated at 54 and 55 in Figs. 6 to 9. Thus the channel 54 is like that at 55 except that it is formed with a top or overlying flange 56 that may carry the knob closure element 57 above referred to. Into the channels is inserted the marginal portion of the fabric 58 of the bag, this fabric lying laterally to conceal the respective flanges 59 and 60 of the frames 54, 55. Prior to the clamping of the frames the top and arm sections thereof appear as in Figs. 6 and 7; after clamping they appear as in Figs. 8 and 9 with the normally concealed flanges 59, 60 bent inward to permanently grip the bag, but with the rest of the frames maintained as before to preserve a neat and decorative appearance.

To cause such bending only of the normally concealed flanges 59 and 60, the jaw member 28 may have an inclined face 61 so that the opposed faces of the jaws diverge downwardly. The corresponding face of the jaw 29 may be at right angles to the seat 27.

After the bag has been inserted in the channels, the top sections 52 of one frame member 50 is placed between the jaws 28, 29 to rest on the inclined seat, with the bag projecting forwardly toward the operator, and the inclination aiding to avoid undue distortion of the bag fabric. This insertion is effected by knee action, the arm 41 causing retraction of the jaw 29; after insertion the arm 41 is released so that the spring 33 advances the jaw 29 to grip and hold the top section 52 to avoid any movement or slippage and consequent scratching or marring of the finish on the frame. Now the final adjustments, if any are required are conveniently made, the operator checking the frame and the insertion of the bag therein. Then the power means is energized so that the head 23 descends to operate the toggle-like member 42 which imparts a powerful kick, like a trigger action, to cause an instantaneous clamping of the frame by deformation of the flanges 59, 60 and a simultaneous adjustment of the knob closure 57 by the abutment 49. Retraction of the member 42 is immediate, and the operator may again operate the arm 41 to retract the jaw 29 for removing the frame. The instantaneous powerful clamping action is so adjusted as to avoid any distortion or cutting of the bag material in clamping.

An important feature of the invention is that the jaws 28, 29 are of sufficient length to engage the entire top section 52 of the frame. In order to also clamp the corner portions 62 of the frame, the jaws may have laterally projecting end portions 63 therefor which extend beyond the seat 27. Of course the seat 27 may extend from arm to arm of the frame to thus directly position the frame, but it may also be narrower if required.

After the top section 52 has been clamped the arms 53 are clamped in an identical machine, which however is different to the extent indicated in Fig. 5. Thus this machine may have a bracket 64 providing a seat 65 narrower than those shown in Fig. 4 but here also the jaws may extend at least at one end to engage the corner portions of the frame, but to clear the hinges 51. Hence in actual use, a plurality of machines are preferably used, one to clamp the top sections, and the other to clamp the arm sections, the

handbag passing from one machine to the other until completed. Preferably two arm clamping machines are provided in relation to each machine that clamps the top sections 52 for a continuous high speed manufacturing procedure. If frames of a different size are to be clamped, the jaws such as 28, 29 may be removed and replaced by others to suit.

I claim:

1. A machine for clamping bags in channelled, U-shaped frames, including a plurality of jaws one of which is movable, and the other of which is relatively fixed, and being so coordinated with the other that the movable jaw is automatically yieldingly urged toward the other for a preliminary clamping action, said jaws providing relatively plane faces which are at an acute angle to each other so as to be adapted to clamp a handbag channel frame by substantially deforming the normally concealed flange of the frame, power means comprising an electric motor for actuating the movable jaw to exert an instantaneous clamping action on the frame, said jaws being of sufficient length to engage therebetween the entire length of a relatively straight section of the frame for thus clamping the same on the bag in one clamping operation, and means separate of the power means for automatically yieldingly urging the movable jaw toward the other jaw independently of the power means, the movable jaw being maintained in operative relation to the power means for actuation by the latter while yieldingly actuated by the said separate means, said power means comprising a frame having a vertical guideway, a reciprocating means in the guideway including a head and a member pivoted to the lower end of the head, a toggle including a pair of arms pivotally connected at one end to the lower end of the member, said arms extending downwardly and angularly in opposite directions from said member, the other end of one arm having pivotal engagement with the frame, the latter having a supporting portion at an angle to the path of the reciprocating means, the supporting portion slidably carrying the movable jaw, a head connected to the movable jaw, the said separate means including an element alongside the toggle arm for the jaw head yieldingly acting directly between the supporting portion and the jaw head, and in aligned relation to the jaw head, the other end of the other toggle arm and the jaw head having lost motion pivotal interengagement, a downward movement of the power head and member causing the toggle arms to move angularly away from each other with the member swinging on its pivot and the toggle moving bodily laterally and projecting the jaw head, with the latter also actuated by the yielding means as aforesaid, and retraction of the power head and member causing retraction of the toggle arm that engages the jaw head while the latter remains in its projected position and continues to be subject to the force of the yielding means.

2. A machine according to claim 1 wherein the said pivotal engagement between a toggle arm and the frame is of lost motion character whereby the toggle is bodily upwardly movable upon retraction of said head and member to thus afford a substantial retraction of the other toggle arm relative to the jaw head.

3. A machine according to claim 1 wherein said supporting portion and said jaw head have stop means to limit movement of the movable jaw toward the fixed jaw under actuation of the yielding means, the actuation of the jaw head by the power means stopping short of the stop means.

4. A machine according to claim 1 wherein a manual means is provided for retraction of the jaw head against the force of the yielding means when the power means is in retracted position, comprising a linkage connected to the head and to the supporting portion, the yielding means being superior to the manual means when the latter is released.

5. A machine according to claim 1 wherein the jaw head is provided with an open cut out forming a guide for the end of the adjacent toggle arm, and manual means for retracting the jaw head against the force of the yielding means, including pivotally interconnected arms having one arm pivotally connected to the jaw head and another arm pivotally connected to the supporting portion, the arm connected to the jaw head extending partially along the said adjacent arm of the said toggle and forming a closure for one side of the cut out to thus retain the said end of said adjacent arm in lost motion engagement with the jaw head.

6. A machine according to claim 1 wherein the said supporting portion is inclined downwardly away from the path of the reciprocating means, the path of the movable jaw being correspondingly inclined, the toggle arm engaging the frame being relatively short, and the toggle arm engaging the jaw head being relatively long.

7. A machine according to claim 1 wherein the angle of the supporting means is obtuse, the toggle arm engaging the jaw head being substantially longer than the companion arm, and the pivotal engagement between the latter and the frame being lost motion in character so as to permit retraction of this arm upon retraction of the power head and member.

8. A machine according to claim 1 wherein the supporting portion provides between the jaws a seating portion for a handbag frame to position the latter in upright relation relative to the jaws, each jaw having end portions projecting in opposite directions from the seating portion to engage the corner portions of a U-shaped frame member resting on the seat, with the jaws being so close to the seat as to be adapted to engage and clamp the frame member.

9. A machine according to claim 1, wherein said supporting portion is downwardly inclined at an obtuse angle to the path of the reciprocating means and affording a correspondingly inclined path for the movable jaw, the toggle arm for the head of the movable jaw being approximately parallel to said path for powerfully moving said jaw, the faces of the jaws being approximately at right angles to said path and the space therebetween opening upward to receive the frame of a handbag.

10. A machine according to claim 1 wherein an adjusting member is fixed on one jaw in such relation to the jaws as to the operative for bending and adjusting a fastener knob on a flange of a handbag frame member coincident with the clamping of the latter.

ERIC M. KASS.
